(57) CLAIM

The ornamental design for a display screen with graphical user interface, as shown and described.

DESCRIPTION

The FIGURE is a front view of a display screen with graphical user interface.

The FIGURE is illustrated to show contrasting appearances. Areas of the graphical user interface that appear in different shades of gray represent areas with a contrasting appearance. The outer dashed broken lines in the FIGURE show a display screen or portion thereof, or an electronic device having a display screen, and form no part of the claimed design.
